BENDING MACHINE WITH PIVOTED BENDER
CARRYING A WORK SUPPORTING ARMWilber E. Pettersen, Akron, Ohio, assignor, by
mesne assignments, to Coleman-Pettersen Cor-
poration, Cleveland, Ohio, a corporation of Ohio

Application November 19, 1945, Serial No. 629,437

5 Claims. (Cl. 153—20)

1

This invention relates to wire-bending machines such as are employed for bending lengths of wire to predetermined configurations comprising one or more bends and a plurality of straight reaches.

Its chief objects are to provide a machine adapted for rapid production of bent wire products of either a single or successively different configurations; to provide a machine adapted for quick and accurate re-setting for products of different configurations and to do that with few and inexpensive parts; to provide for automatic manipulation by the machine of parts of the wire lengths anterior to the bending operation; to provide for power operation, as distinguished from manual operation, of the machine; and to provide for ready control of the amount of force applied in the bending operation in accordance with the bend-resistance of the wire being operated upon, so as to bend the wire only to such form that upon release of the bending force the wire will recoil accurately to the configuration desired in the product.

Of the accompanying drawings:

Fig. 1 is a plan view of a machine embodying my invention in its preferred form, parts being broken away for clearness of illustration.

Fig. 2 is an elevation of air-supplying devices constituting a part of the machine shown in Fig. 1.

Fig. 3 is an end elevation of the machine with parts broken away and with parts sectioned on line 3—3 of Fig. 1.

Fig. 4 is a fragmentary section on line 4—4 of Fig. 1.

Fig. 5 is a section on line 5—5 of Fig. 1.

Fig. 6 is a section on line 6—6 of Fig. 1.

Fig. 7 is a side elevation of the machine, with parts broken away and with a part in section on line 7—7 of Fig. 1.

Referring to the drawings, the machine comprises a metal slab or table 10 suitably supported by a frame 11 but with a clearance space of considerable vertical dimension between the table 10 and the frame 11 throughout a large part of the lower right-hand part of the table as viewed in Fig. 1. This clearance, for the horizontal swinging movement of a work-supporting arm, can be visualized in looking at Figs. 3 and 7. (Note the table-supporting members 10a and 10b in those figures.)

Fixedly seated in a transverse guide-groove 12 formed in the upper face of the table and held by a cap-screw 13 extending through the floor of the groove (Fig. 4) is a bending-jaw member 14

2

which has a rectangular base portion fitting in the groove 12 and a triangular upper portion projecting upward from the upper face of the table and providing an acute angled vertical edge 14a for the bending of the wire about it.

A companion bending-jaw member 15 mounted for sliding adjustment in the groove 12 is formed with a downwardly sloping rear face which is notched to provide a seat for the end of an adjusting bolt 16 which is threaded through a bracket 17 secured to an edge face of the table. For holding the bending-jaw member 15 in its positions of adjustment a clamping bolt 18 extends vertically through it and through a slot 19 formed in the floor of the groove 12.

The bending-arm, 20, adapted to coact with the jaws 14, 15, is secured on the upper end of a shaft 21 journaled in a bushing 22 (Fig. 3) which is mounted in the table and secured on the lower end of the shaft 21 is a gear 23 which is meshed with a rack 24. The rack is guided and held in mesh with the gear by a bracket 25 extending downward from the table and the rack is coupled to the piston rod 26 of a double-acting air cylinder 27 mounted under and supported from the table.

Secured to the under side of the gear 23 by means of two spacing brackets such as the bracket 28 (Fig. 3), welded to respective spokes 30 of the gear, is a sleeve 29 in which is secured, by a set-screw 30, the inner end of a horizontal rod 31 the outer end of which extends beyond the adjacent end of the table and has secured thereon a vertical wire-supporting bracket 32 formed with an upwardly open wire-receiving notch 33 in its upper end. The construction preferably, as shown, is such that when the parts are in the starting position of Fig. 1 the rod 31, off-set from the axis of the bending-arm 20, is also off-set 40 slightly from the wire-receiving notch between the bending-jaws 14, 15, so that normally straight portions of wires closely fitting in that notch and in the notch 33 of the bracket 32 are held in a slightly bent condition, which helps to keep a plurality of wires accurately stacked in the notches and this avoids the necessity of substituting a different bracket 32 for every diameter of wire operated upon.

The off-set position of the rod 31 with relation 50 to the axis of the bending-arm 20 compensates for the fact that said axis preferably is spaced at a substantial distance from the jaw-edge 14a about which the wire is bent, so that in the working movement the arm 20 contacts the wire at positions progressively nearer the lip 14a and the

said off-setting is such that throughout the bending operation, whether the wire is bent to more or less than a right-angle, or to a right-angle, the bending edge 14a, the bending lip 20a of the jaw, and the notch 33 of the bracket 32, will be approximately in alignment at all times, as illustrated by the dotted line position of the rod in Fig. 1.

The usual end-stops 34, 34 for the wires are mounted in a through slot 35 formed in the table, each stop being formed, as clearly shown in Fig. 5, with a slot-fitting tongue non-symmetrically positioned on its lower end, and is held in selective positions of adjustment by a screw or bolt 36 extending vertically through it at the position of its tongue and screwed into a tongued or flanged nut 37 fitting into the slot from below. The stops are thus adapted to be set in a position, as in the case of the right-hand one in Fig. 1, such that a straight reach of wire from the jaws 14, 15 can extend past it. For acting as stops against the side faces of portions of the wires posterior to the bending jaws 14, 15, one or more eccentrically mounted cylindrical blocks such as the block 38 is or are mounted upon the upper face of the table, the block being held in selectively different rotative positions about its eccentric axis by a screw 39 extending vertically through it and screwed into one of a spaced series of tapped holes, 40, 40 extending part way through the table, as shown clearly in Fig. 6. As each block is adapted for infinitely small increments of adjustment, and can be set in one or another of the holes of the series, a single, straight row of the holes 40 is sufficient for the usual range of operations.

Similarly the table is formed with a field of spaced holes 40a, 40a near the bending jaw 14 for the mounting in that region, at locations determined by the holes and in selective rotative positions, a cylindrical, eccentrically mounted block 38a corresponding to the block 38 as just described, the block 38a being adapted to act as a stop against the portion of the wire anterior to the jaws 14, 15 and by its resistance, through the stiffness of the wire, to stop the bending-arm 20 at a position such that the wire will have permanent set with the desired angle of permanent bend. The block 38a is of such size and of such eccentricity, in relation to the positioning of the holes 40a, that infinitely small variations of adjustment can be had throughout the required range of operations.

For actuating the pressure-fluid cylinder 27, a treadle 41, operable from either side of the table, is hinged on a middle axis 42 (see Figs. 3 and 7), to the end structures of the frame and each side of it is connected by a pull-cable 43 with the lever 44 of the cylinder's four-way control valve 45 having exhaust vents 45a, 45b for the two ends of the cylinder.

For supplying compressed air to the cylinder an air supply pipe 46 (Fig. 2) from a suitable source leads, through a filter 47, a regulator valve 48, an oiler 49 and a pipe 50, to the four-way control valve 45 of the cylinder.

The regulating valve 48 is adapted to maintain a constant air pressure in the pipe 50 according to the setting of the valve, and the valve is set for such pressure in relation to the bend-resistance of the wire that the bending arm 20 will have only such force as to bend the wire to a position determined by the position of the block 38a without imparting permanent set to the wire between its bend at the bending edge 14a and the block.

The proper pressure in the pipe 50 of course depends upon both the diameter of the wire operated upon and the number of wires in the stack and also in some cases and to some extent upon the length of the reach of wire between the bending edge 14a and the block 38a.

The operation of the machine is as follows: The rack 24 being in its right hand position as viewed in Fig. 1 and the work-contacting members consequently being in the positions in which they are there shown; the wires 100, 100, that are to be bent, of which three are shown in Fig. 7, are mounted in stacked relation as is shown in Fig. 7 and in contact with the several work-engaging members as shown, with regard to the top one of the wires, in Fig. 1.

The left-hand one of the stops 34 (Fig. 1) is in its end-stop position and is abutted by the adjacent ends of the wires; the right-hand one of the stops 34 is in such position that it permits the wires to extend past it and does not serve as an end-stop; and the eccentric block 38, the acute-angled bending-jaw member 14 and a vertical wall of the notch 33 in the bracket 32 serve as three-point lateral supports for the stack of wires, which are in a slightly bent condition by reason of the off-set of the rod 31 and the notch of its bracket 32, as above described, and, as above stated, the bending strain upon the stack of wires helps to keep a plurality of wires accurately stacked in contact with those three members for concurrent action upon them by the bending arm 20.

The work and the bending instrumentalities being as just stated, the cylinder 27 is charged to move the rack 24 to the left as viewed in Fig. 1, which causes rotation, clockwise as there viewed, of the gear 23, the bending arm 20 and the wire-supporting rod 31, which bends the wires 100 to the shape that is indicated by dotted lines in Fig. 1.

The work-supporting bracket 32 clears the corner of the table 10 by reason of the fact that it, as well as the corner of the table, is at a long radius from the shaft 21, as contemplated by the break-away lines near the right-hand end of Fig. 1.

As above stated, the pressure of air supplied to the cylinder is so controlled by means of the regulating valve 48 that the eccentric stop 38a, in being contacted by the swinging portions of the wires, limits the movement of the bending arm 20, and this provision for so limiting it, with fine adjustability of the eccentric stop 38a, provides conveniently for great accuracy in bending successive stacks of wires to the same shape, as contemplated in one part of the above statement of objects.

Upon completion of the operation as just described the bent wires are removed from the machine, for further manipulation or for use in the form to which they have been bent, and the cylinder 27 is then reversed to return the moving parts of the machine to the wire-receiving positions in which they are shown in Fig. 1.

65 I claim:

1. A bending machine comprising stationary members for engaging opposite faces of a length of wire to maintain the position of a portion of the wire, a movable bending member for coacting with said stationary members for bending the wire, a pressure-fluid cylinder for actuating said bending member, an adjustable stop adapted to be engaged by the moving portion of the wire, only and at all times at a greater distance from the bending position than that of the said bend-

ing member's engagement with the wire, to limit the movement of said portion, wholly by such engagement, and thus to stop the said bending member wholly through bending-resistance of the wire, and means for so controlling the maximum pressure of fluid supplied to said cylinder, in appropriate relation to the bend-resistance of the wire, that said stop is effective to limit the movement of the bending member without distortion beyond its elastic limit of wire between said bending member and said stop.

2. A bending machine comprising stationary members for engaging opposite faces of a length of wire to maintain the position of a portion of the wire, a movable bending member for coacting with said stationary members for bending the wire, a pressure-fluid cylinder for actuating said bending member, an adjustable stop adapted to be engaged by the moving portion of the wire, only at a distance from the bending position, to limit the movement of said portion wholly by such engagement, a work-supporting member engaging the wire still farther from the bending position and moving in correlation with the bending member for supporting and controlling the movement of the moving portion of the wire, and means for so controlling the maximum pressure of fluid supplied to said cylinder, in relation to the bend-resistance of the wire, that said stop is effective to limit the bending movement of the bending member without distortion beyond its elastic limit of wire between the bending member and said work-supporting member.

3. A bending machine comprising stationary members for engaging opposite faces of a length of wire to maintain the position of a portion of the wire, a pivotally mounted bending member for coacting with said stationary members for bending the wire, means for moving said bending member about its pivotal axis for bending the wire and work-supporting means pivotally mounted on the same axis with the bending member for movement therewith and engaging the moving portion of the wire at a position more remote from the bending position than is that of said bending member, the said work-supporting member having a face for forcing the wire in the direction of the bending movement and said face being, at starting position, so off-set as to hold the wire under a light bending strain, within its elastic limit, before the functioning of said bending member.

4. A bending machine comprising stationary members for engaging opposite faces of a length

of wire to maintain the position of a portion of the wire, a movable bending member for coacting with said stationary members for bending the wire, means for applying a determinately limited actuating force to said bending member, and stop means engaging the wire only and always at a position farther from the bending position than that of the bending member's wire-engaging part and acting wholly by applying only bending force to the moving portion of the wire and being the only means for stopping the movement of the bending member.

5. A bending machine comprising stationary members for engaging opposite faces of a length of wire to maintain the position of a portion of the wire, a pivotally mounted bending member for coacting with said stationary members for bending the wire, a shaft constituting a mounting for said bending member, a drive member coaxially secured to said shaft, and a work-supporting arm rigid with said bending member, shaft and drive member to move therewith and extending to a position farther from the shaft than that of the bending member's wire engaging part, for engaging the wire at that farther position.
